UNITED STATES PATENT OFFICE.

JOHN S. GREENE, OF ROCHESTER, NEW YORK, ASSIGNOR TO COMMERCIAL CAMERA COMPANY, OF PROVIDENCE, RHODE ISLAND, A CORPORATION OF RHODE ISLAND.

PHOTOGRAPHIC-PRINT-TREATING APPARATUS.

1,102,737.

Specification of Letters Patent.

Patented July 7, 1914.

Application filed March 7, 1912. Serial No. 682,195.

To all whom it may concern:

Be it known that I, JOHN S. GREENE, of Rochester, in the county of Monroe and State of New York, have invented certain new and useful Improvements in Photographic-Print-Treating Apparatus; and I do hereby declare the following to be a full, clear, and exact description of the same, reference being had to the accompanying drawings, forming a part of this specification, and to the reference-numerals marked thereon.

My present invention relates to photography and more particularly to the treatment of photographic prints and negatives in liquid baths, and it has for its object to provide improved means for effecting a quick transfer of the prints from one receptacle to the other which will offer greater convenience to the operator, prevent injury to the print and insure its proper immersion in the bath.

A further object of the invention is to provide an apparatus of the character indicated adapted for the day-light method of treating the prints, particularly when fed to the apparatus from an automatic or mechanical device, such as a camera, that exposes a strip of sensitized material, severs the exposed portion and delivers it for treatment.

To these and other ends the invention consists in certain improvements and combinations of parts all as will be hereinafter more fully described, the novel features being pointed out in the claims at the end of the specification.

In the drawings: Figure 1 is a longitudinal central section through a treating apparatus constructed in accordance with and illustrating one embodiment of my invention, the parts being shown in one position; Fig. 2 is a similar view with the parts in another position; Fig. 3 is a top plan view of one of the receptacles, and Fig. 4 is a detail, enlarged section taken substantially on the line 4—4 of Fig. 3.

Similar reference numerals throughout the several figures indicate the same parts.

In the present embodiment of the invention I have illustrated the apparatus in connection with an automatic exposing or printing machine of the type above referred to, a conventional representation of which is indicated at 1. This machine delivers the

exposed negative or print 2 by any suitable means into a developing receptacle or tank 3 arranged immediately below the same and containing a suitable developing agent. What may be termed the rear end 4 of the receptacle 3 is the end from which the print is withdrawn for subsequent treatment, usually through a small opening 5 at the bottom of the casing of the machine 1 and arranged adjacent to said end 4 is the end 6 of an intermediate receptacle 7 that, in the present instance, is used for washing the print. The rear end 8 of this intermediate receptacle 7 abuts the front end of the receptacle 9 into which the print is finally introduced for fixing with hypo. One of the two abutting end walls in each instance is preferably provided with a depending apron 10 to prevent leakage of the liquid between the receptacles.

In the practice of my invention I provide the intermediate receptacle 7 near its front end 6 with receiving guides for the print as it leaves the receptacle 3. These guides, in the present instance, comprise a pair of aligned rollers 11 preferably raised above the rim of the receptacle and journaled upon the opposite end of a bail 12 extending transversely of the receptacle 7 and supported in any suitable manner, as upon uprights 13. The intermediate portion of the bail 12 is offset downwardly, as at 14, for a purpose that will hereinafter appear so that in effect the two receiving guides or rollers 11 are spaced apart at their proximate ends. At a preferably intermediate point the receptacle 7 is also provided with a transversely extending immersing member in the present form of a roll 15 carried at opposite ends by suitable linked supports 16, that are in turn pivoted at their upper ends at 17 to suitable supporting standards 18. The normal position of the immersing member 15 is below the surface level of the receptacle 7, as shown in Fig. 2, but the pivots 17 are above the surface level and also preferably above the rim of the receptacle.

In operation, the print 2, after being developed, is brought to the position shown in Fig. 1 in which its edge is just above the adjacent rims of the receptacles 3 and 7. The operator then displaces the immersing member 15 by thrusting his hand beneath it and moving it upwardly to approximately

the position shown in Fig. 1 in which it is adjacent to the receiving guide rolls 11 and above the offset portion 14 of the bail 12. He can then thrust his fingers between 5 the ends of the rolls 11 and grasp the edge of the print, withdrawing it from the receptacle 3, over the guide rolls 11 and down into the water bath in the receptacle 7. As he continues to draw the print rear- 10 wardly, the immersing member follows by gravity and, in dropping, thrusts the body of the print below the surface of the water in the receptacle and continues to hold the dragging portions immersed throughout the 15 passage of the print through this intermediate receptacle, and while the operator is introducing the advance edge over a suitable guide roller 19 at the end 8 of the receptacle 7 and into the final or fixing bath 20 in the receptacle 9. It will be seen, therefore, that this transfer from the developing receptacle 3 through the intermediate receptacle and into the hypo, can be effected with a quick movement and in a very short 25 space of time so that even though the receptacles 7 and 9 are exposed to light the print can undergo very little change before being fixed, while the washing operation in the intermediate receptacle 7 is sufficiently 30 thorough to greatly lessen the deterioration of the hypo, which deterioration is rapid when a direct transfer is made from the developer thereto. The rolls 11, 15 and 19 provide smooth and even frictional surfaces 35 for the wet and soft print, and the immersing member 15 acts automatically in immersing the last half of the print just as effectively as the operator's hand immerses the front half while being very readily dis- 40 placed, and thus offering little inconvenience to the operator when reaching for the print in the first instance.

I claim as my invention:

1. In an apparatus of the character de- 45 scribed, the combination with a suitable receptacle for the fluid bath, of supporting links pivoted to the receptacle on opposite

sides thereof at points above the surface level, and a transversely extending immersing member carried by the lower ends of 50 the links in a normal position below the surface level.

2. In an apparatus of the character set forth, the combination with a suitable receptacle for the fluid bath, of a transversely 55 extending receiving guide at one end of the receptacle arranged above the rim thereof, supporting links pivoted at opposite sides of the receptacle at points above the surface level and a transversely extending im- 60 mersing member carried by the lower ends of the links in a normal position below the surface level but adapted to swing upwardly to a position adjacent to the receiving guide.

3. In an apparatus of the character de- 65 scribed, the combination with a suitable receptacle for the fluid bath, of a pair of transversely extending aligned receiving guides at one end of the receptacle having a space between them, a transversely ex- 70 tending immersing member mounted on the receptacle having a normal position below the surface level and means for moving the immersing member from its said normal position upwardly to a position adjacent to 75 the receiving guides.

4. In an apparatus of the character de- 80 scribed, the combination with a suitable receptacle for the fluid bath, of a transversely extending bail at one end of the receptacle provided with an offset intermediate portion, guide rolls journaled on the end portions of the bail, a transversely extending immersing member mounted on the receptacle having a normal position below the 85 surface level and means for moving the immersing member from its said normal position upwardly to a position adjacent to the guide rolls and above the offset portion of the bail.

JOHN S. GREENE.
